UNITED STATES PATENT OFFICE

ANGELO C. SCAVULLO, OF GREAT KILLS, NEW YORK, ASSIGNOR TO ARTHUR SCHILLER & SON, A CORPORATION OF NEW YORK

DESIGN FOR A PLATE OR SIMILAR ARTICLE

Application filed June 16, 1931. Serial No. 40,223. Term of patent 7 years.

To all whom it may concern:

Be it known that I, ANGELO C. SCAVULLO, a citizen of the United States, residing at Great Kills, county of Richmond, city and State of New York, have invented a certain new, original, and ornamental Design for Plate or Similar Article, of which the following is a specification, reference being had to the accompanying drawing forming a part thereof, in which Figure 1 illustrates a portion of a plate on which my design is placed, the design being continuous on the entire margin of a plate or similar article, as indicated in Fig. 2.

I claim:

The ornamental design for a plate or similar article as shown, and described.

Signed this 15th day of June, 1931.

ANGELO C. SCAVULLO.
